The ornamental design for a key fob, as shown and described.

DESCRIPTION

FIG. 1 is a perspective view of a key fob showing my design;
FIG. 2 is a top plan view thereof;
FIG. 3 is a bottom plan view thereof;
FIG. 4 is a left end elevational view thereof; and,
FIG. 5 is a right end elevational view thereof.
The broken line showing of a partial key, in FIGS. 1-3, is for
illustrative purposes only and forms no part of the claimed
design.
